UNITED STATES PATENT OFFICE.

HERMAN EDWARD STÜRCKE, OF BROOKLYN, NEW YORK.

AIR-BRUSH AND SIMILAR APPARATUS.

1,294,190.

Specification of Letters Patent. Patented Feb. 11, 1919.

Application filed May 13, 1916. Serial No. 97,376.

To all whom it may concern:

Be it known that I, HERMAN EDWARD STÜRCKE, a citizen of the United States of America, residing at 220 Carroll street, 5 Brooklyn, New York, in the county of Kings and State of New York, have invented certain new and useful Improvements in Air-Brushes and Similar Apparatus, of which the following is a specification.

10 This invention relates to improvements in means for regulating the flow and mixture of fluids, or mixtures of fluids and solids, and is particularly applicable for use in connection with apparatus in which a regulated stream passes through a nozzle or the like, as in spraying or atomizing devices; the invention relates more particularly to improvements in spraying or atomizing devices and especially for the air brushes or 15 pistols which are employed in the art of painting or for like purposes in well-known manner; but while the invention is particularly applicable to the art of painting, and a preferred embodiment of the invention as 20 applied to this purpose will be hereinafter described, it is to be understood that the invention is equally of value in connection with all types of spraying or atomizing apparatus, and apparatus in which the mixture of two or more substances is regulated, as for instance, oxyacetylene blow-pipes and 25 the like.

30 Among the objects of the invention are to provide improved means for regulating the mixture and flow of substances; to provide improved means for insuring a uniform atomizing effect; to provide a simple apparatus which, when once adjusted, can be operated by a simple movement of a single 35 operating member; and to provide a simple and inexpensive structure, the internal parts of which are readily accessible for renewal, repair or adjustment.

40 A preferred embodiment of the invention as applied to a painting tool or pistol will now be described with reference to the accompanying drawings, in which:—

Figure 1 is a side elevation of the spraying tool.

45 Fig. 2 is an end-elevation, looking in the direction of the arrow A of Fig. 1.

Fig. 3 is a cross-section on line b—b of Fig. 2; and

50 Fig. 4 is a cross-section on line c—c of Fig. 3.

Figs. 5 and 6 show different positions of adjustment of the regulating means.

Referring to the drawings, it will be seen that the painting tool comprises a body portion 1 and a handle 2. The body portion 60 is bored to provide a paint chamber 3 and an air chamber 4; threaded to the inner wall of the paint chamber 3 is paint nozzle 5, which in turn is surrounded by air nozzle 6, which latter nozzle is threaded to body portion 1 in the manner shown. An annular recess 7 is formed in the body portion between the nozzles 5 and 6, and forms with the inside wall of nozzle 6, an annular chamber 8 for a purpose hereinafter explained. 65 Air chamber 4 communicates with said annular chamber 8 by means of a passage 9 controlled by the air valve 10, which passage 9 leads into two passages 11 (Fig. 4) leading to the bottom of annular recess 7. 70 Air is supplied to the air chamber 4 through flexible connections 12, connecting-piece 13, tube 14 in handle 2, and passage 15 in body 1. Paint is supplied to chamber 3 through the passage 16 to the walls of which is attached a paint-pot 17.

75 The flow of paint and air to the respective nozzles is controlled by the paint valve 18 and the air valve 10. The valve 18 is mounted on a circular valve stem 19 which passes through the gland 20 with leather packing 21 arranged in the body, and extends at its rear outer end through the bearing piece 22 carried by the projecting lug 23 on the body 1, said valve being normally maintained 80 closed by means of the compression spring 24 bearing at one end against the face of a recess 25 in said bearing piece 22, and bearing at its other end against an annular ring 26 connected to said valve stem 19 by pin 27. 85 The air valve 10 comprises a conical top 27' mounted on an octagonal guiding head 27^a carried on stem 28 passing through bearing ring 29 and packed by a leather washer 30, which can be compressed by gland 31. A 90 coil spring 32 bearing against ring 29 and the hexagonal guiding head normally maintains said air valve in closed position. Pivoted to lug 33 on the body 1 by pin 34 is a trigger 35 which is connected by means of a yoke piece 36 with a bifurcated valve-actuating member or plate 37, shown more clearly in Fig. 2, the arms of which embrace the valve rods 19 and 28. It will be noted 95 that the outer or ear ends of these valve rods 100 105 110

19 and 28 are threaded at 38 and 39, and mounted on said ends are the milled regulating nuts or abutments 40, 41, and lock nuts 42, 43; said nuts 40 and 41 can be adjusted to various positions along the threaded ends 38 and 39 and the operation is such that on applying pressure to the trigger 35 and moving same toward handle 2, the slotted plate 37 will bear against said nuts 40 and 41 and thereby open the air and paint valves to the required extent. After the desired position of adjustment has been obtained, the lock nuts 42 and 43 are brought into position to maintain the nuts 40 and 41 against movement.

As a result of the construction above described, a number of novel regulating effects may be had with the utmost ease of manipulation. For example, if it is desired to provide a maximum or substantially maximum opening for both paint and air, both regulating nuts can be screwed forward as far as possible to the left, as shown in Fig. 1, so that the full working stroke 20 of the trigger 35 will be applied to the valve stems to cause said valves to open to their maximum extent. On the other hand, if it is desired to effect a minimum opening of the air and paint valves, the nuts can be adjusted toward the rear ends of the valve stems, as shown in Fig. 3, so that the first 25 part of the stroke of the trigger 35 is ineffective and merely carries plate 37 into contact with the regulating nuts, which are moved only during the final portion of the trigger stroke, thereby opening said valves only to the minimum extent. A range of adjustment between these described maximum and minimum openings of the valves 30 can be had by intermediate positioning of the nuts 40, 41.

In addition to providing for a simultaneous range of adjustment for the two valve members, as described above, it is also possible by means of my regulating improvement to provide for independent adjustment of the valves in order that not only may the stroke of each valve differ one from the other, but also the timing relation of 45 opening one valve as compared with the other. For example, as shown in Fig. 5, the air regulating nut 41 may be located in advance of the paint regulating nut 40, so that during the first part of the stroke of 50 trigger 35, the nut 41 will be carried toward the rear by the plate 37, thereby opening the air valve without opening the paint valve, so that the air can clear away any impediments which may exist in the aperture of 55 nozzle 6. Continued movement of the trigger causes the abutment of plate 35 against nut 40, thereby moving said nut toward the rear and opening the paint valve. It will be noted that the extent of opening of the 60 air valve will be greater than that of the 65

paint valve, owing to the fact that the air-regulating nut is moved through a greater distance than the paint-regulating nut. It will be obvious that the paint valve might be opened before the air valve, and that any 70 desired adjustment of the extent of opening may be had without changing the timing relation between the operation of the two valves. For instance, as shown in Fig. 6, by screwing the nuts toward the rear ends 75 of the threaded valve stems, with the position of the nut 41 relative to the nut 40 the same as that shown in Fig. 5, that is to say, with nut 41 in advance of nut 40, the timing operation will be the same as that described 80 with reference to Fig. 4, but the extents of opening of the two valves will be lesser, as only the latter portion of the stroke of trigger 35 will be effective to open the valves. It will therefore be appreciated that the invention provides a single operating member or trigger which, by a simple movement on the part of the operator, will always cause the tool to work with the adjustment to which it has been set, and the regulating 85 means permit of numerous combinations of 90 adjustments throughout all possible useful ranges.

It will be noted that the sides of the valve stems 19 and 28 are cut away at the rear 95 ends, as shown in Fig. 2, in order that they may fit into the rectangular slot in plate 37. This engagement between the two flat side faces of the valve rods and the flat faces of the slot prevents any turning movement of the valve stems which would otherwise occur were the nuts 40 and 41 to become rusted or stick to the threaded ends. It also assists in guiding the correct axial movement of the valve stems.

In order that the tool may bear against the hand of the operator, a rest plate 44 is interposed between the handle 2 and body portion 1. One important feature of the present invention resides in the even distribution of the pressure air as a result of providing the annular chamber 8, and the consequent even atomization of the paint. As described above, the air flows into this annular chamber 8 through the two passages 11 at the bottom of the chamber, and from thence the air flows out through the nozzle 6, at the aperture of which it meets the paint issuing from the paint nozzle 5. It will be noted that the edge 45 of the nozzle 6 comes 115 almost in contact with the edge 46 of the nozzle 5, thereby providing a restricted annular passage for the air and somewhat blocking the free flow of this air, so that when the air from the passages 11 flows into 120 the chamber 8, it cannot all escape from said chamber at the point where it flows in, and as a consequence, some of said air flows into the upper part of said chamber 125 and passes out evenly through the restricted 130

annular opening between the edges 45 and 46. Were it not for the provision of this restricted annular opening, the air coming in through the passages 11 at the lower part of 5 the nozzle would tend to flow out immediately and directly along the lower surface of the nozzle, and as a consequence, the paint issuing at the top part of the nozzle aperture would not be atomized as thoroughly 10 as that issuing at the lower part of the aperture. It will therefore be appreciated that the invention provides for the even distribution of the air as it passes out from the nozzle, and a consequent even atomization 15 of the paint.

Should it become desirable to renew or replace the valve stems 19 or 28, or to replace the springs 24 or 32, it is only necessary to rotate the yoke piece upwardly 20 around the pin 47 which pivotally connects it with the trigger 35. The plate 37 is thereby disengaged from the valve stems; the bearing piece 22 is then unscrewed, after which the valve spring 19 and valve stem 25 can be removed. The air valve can be removed by the simple expedient of unscrewing the gland 31.

It will be obvious that my improved apparatus is susceptible of considerable modification without departing from the spirit and the scope of the invention, and I wish it to be understood that the preferred embodiment described herein is offered by way of example only.

35 What I claim is:

1. In a device of the character described, a plurality of outlet means, a plurality of valve members, a plurality of valve stems, a valve operating member common to all 40 said valves, a bearing member carried by said operating member, and abutments mounted on said stems, said abutments being adjustable toward or away from the bearing member.

45 2. In a device of the character described, a plurality of nozzles, valves for said nozzles, a plurality of valve stems, abutments adjustably mounted on said stems, a common valve opening member, and a rectilinearly moving bearing member carried by said opening member and adapted to engage with the adjustable abutments on the valve stems to impart different increments of movement to said valves.

50 3. In a device of the character described, a pair of concentric nozzles, a body supporting said nozzles and comprising a pair of chambers communicating with said nozzles, valves in said chambers, a pair of stems for said valves, individually adjustable abutments mounted on said stems, means normally tending to maintain said valves closed, an operating member for opening both said valves and a rectilinearly moving bearing member carried by said

operating member and adapted to engage with the adjustable abutments on the valve stems to open said valves.

4. In a device of the character described, a pair of nozzles, a pair of valves for said nozzles, having threaded portions, a movable operating member, a bearing piece carried by said operating member and nuts on said threaded portions, said nuts being adjustable toward or away from the bearing member and adapted to engage with the same to transmit motion from said operating member to said valves through said nuts.

5. A device of the character described, comprising in combination with the body, a handle, a pair of nozzles, a pair of valves arranged in the body and provided with valve stems having threaded portions, an operating member pivoted to said body, a bearing member pivoted to said operating member and a pair of nuts on said threaded portions, said nuts being adjustable toward or away from the bearing member and adapted to engage with the same to transmit motion from said operating member through said nuts to the valve stems to open the valves.

6. In a device of the character described, a pair of nozzles, a body portion supporting said nozzles and having passage-ways formed therein, an operating member connected thereto, a pair of valves in said body controlling said passage-ways, springs normally maintaining said valves in closed position 100 and maintaining said operating member in normal position, a pair of stems for said valves, individually adjustable abutments on said valve stems and a rectilinearly moving bearing member carried by the said operating member, and adapted to engage with the adjustable abutments to open said valves against the action of said valve springs.

7. In a device of the character described, a plurality of nozzles, valves for said nozzles, a plurality of stems for said valves, abutments adjustably mounted on said valve stems, a valve-opening member common to all said valves, and a rectilinearly moving bearing member carried by said operating member and adapted to engage with the adjustable abutments to open said valves and to vary the time sequence of the opening of the valves.

8. In a device of the character described, a plurality of nozzles, valves for said nozzles, a plurality of stems for said valves, abutments adjustably mounted on said valve stems, a valve-opening member common to all said valves, and a rectilinearly moving bearing member carried by said operating member and adapted to engage with the adjustable abutments to open said valves and to vary the time sequence and extent of opening of the valves.

9. In a device of the character described, the combination with a body of a nozzle supporting portion, an annular recess in said portion, an inner nozzle located concentrically relative to said recess and supported on said nozzle-supporting portion of the body, an outer nozzle located concentrically relative to said inner nozzle and having a cut-away portion at its inner end, an annular shoulder on said inner nozzle, the walls of said annular recess, cut-away portion and shoulder constituting an annular chamber with a restricted annular outlet, the body being formed with passage-ways, one or 10 more leading to said annular chamber and the other to said inner nozzle, valves for controlling said nozzles, stems for said valves, adjustable abutments mounted on said valve stems, an operating member common to 15 all the valves, and a rectilinearly moving bearing member carried by said operating member and adapted to engage with the adjustable abutments to open said valves.
10. In a device of the character described, 20 the combination of an inner nozzle having a shoulder on its outer face, an outer nozzle concentric with said inner nozzle and having its inner face located in close proximity with said shoulder, said nozzles being formed to 25 provide an annular chamber at the base

thereof, a body supporting said nozzles and formed with passage-ways, one leading to the inner nozzle and the other to a point within said annular chamber, valves for controlling said nozzles, stems for said valves, 30 adjustable abutments mounted on said valve stems, an operating member common to all the valves, and a rectilinearly moving bearing member carried by said operating member and adapted to engage with the adjustable abutments to open said valves. 35

11. In a device of the character described, the combination of a pair of concentric nozzles formed to provide an annular chamber between the nozzles and said chamber opening into the restricted space between the outer and inner nozzle, a body supporting said nozzles and formed with passageways, one leading to said annular chamber and the other to said inner nozzle, valves for 40 controlling said nozzles, stems for said valves, adjustable abutments mounted on said valve stems, an operating member common to 45 all the valves and a rectilinearly moving bearing member carried by said operating member and adapted to engage with the adjustable abutments to open said valves. 50

In testimony whereof I affix my signature.

HERMAN EDWARD STÜRCKE.
